UNITED STATES PATENT OFFICE.

KENNETH D. LOOSE, OF BOSTON, MASSACHUSETTS, ASSIGNOR TO LOOSE-WILES BISCUIT COMPANY, OF NEW YORK, N. Y., A CORPORATION OF NEW YORK.

CONTINUOUS DOUGH SHEETING AND FEEDING MECHANISM.

1,134,971.

Specification of Letters Patent.

Patented Apr. 6, 1915.

Application filed January 8, 1915. Serial No. 1,211.

To all whom it may concern:

Be it known that I, KENNETH D. LOOSE, a citizen of the United States, and a resident of Boston, in the county of Suffolk and State 5 of Massachusetts, have invented an Improvement in Continuous Dough Sheeting and Feeding Mechanism, of which the following description, in connection with the accompanying drawings, is a specification, 10 like characters on the drawings representing like parts.

This invention relates to mechanism for producing continuous sheets of dough for biscuits or like manufacture, and is an improvement upon the mechanism disclosed in 15 the co-pending application of Edward E. Lawrence, Serial No. 832,397, filed April 16, 1914.

In order that the principle of the invention 20 may be readily understood, I have disclosed a single embodiment thereof in the accompanying drawings, wherein:

Figure 1 is a side elevation of the right hand or operating side of a mechanism constituting one embodiment of my invention; Fig. 2 is a similar view of the left hand or driving side of the mechanism; Fig. 3 is a longitudinal vertical section of the mechanism shown in Fig. 1; Fig. 4 is a front or 25 receiving end view of the mechanism shown in Fig. 1; Fig. 5 is a plan view of the mechanism shown in Fig. 1; Fig. 6 is a horizontal, longitudinal section on the line 6—6 of Fig. 1; Fig. 7 is a plan view of a portion of 30 the roller driving mechanism, the aprons or belts being removed; and Fig. 8 is a side elevation on an enlarged scale of a portion of the delivery end of the mechanism.

Prior to the invention on which this is an 40 improvement, as above stated, it has been the practice to prepare sheets of dough for biscuit cutting and like machines by feeding a mass of dough between a single pair of rollers which are driven first in one and 45 then in the opposite direction, so that the mass is brought into sheet form by being passed back and forth and therefore repeatedly between said rollers. Not only are two persons required to feed the sheet or layer 50 back and forth until the proper thickness thereof is obtained, but such sheets are of comparatively short lengths, and in order to feed sheet-like material continuously to the biscuit cutter or other machine, it has been 55 necessary to lap the sheets, this having been

done customarily at intervals of about thirty inches. These lapped sheets were passed between the so-called gaging rolls of the biscuit cutting or other machine. This lapping operation was very objectionable, in 60 that thicker biscuits or products resulted at their lapped zones. These thicker biscuits would not bake as readily as those formed from the thinner portions of the sheet, and hence either the thicker biscuits were under- 65 baked, or if they were properly baked, then the thinner biscuits were overbaked or burnt. In order to overcome this and other objections, I have in accordance with my invention devised improved mechanism where- 70 by the dough mass is formed into a continuous sheet, which may be fed in an indeterminate length to the gaging rolls of the biscuit cutting mechanism.

Referring more particularly to the drawings and first to the longitudinal vertical section represented in Fig. 3, I have therein indicated the framework as composed of metallic or other suitable side members indicated generally at 1 and connected in any 80 suitable manner and wherein the various operating parts are mounted. For convenience of description, I shall hereinafter refer to the receiving end of the apparatus as the front end thereof and to the delivery 85 end as the rear end thereof.

As pointed out in said Lawrence application, wherein the mechanism forms a continuous sheet of dough by compression, certain doughs after compression contract and 90 other doughs continue to flow, this depending generally upon the amount of sugar. A dough containing a small proportion of sugar generally contracts after compression, and one containing a relatively high proportion of sugar generally expands or flows after compression. Such action of the dough is herein termed generally a self-readjustment of the constituents thereof. In order to secure such self-readjustment which must 100 for best results be effected before the biscuits are severed from the sheet, it is important that the dough sheet be freed from and preferably removed from the belt or belts against which it was compressed, and to 105 which it has stuck during and incidental to such compression, so as to prevent the self-readjustment desired, and that it be delivered without breakage or deformation to another surface. As the continuous dough 110

sheet passes from the belt against which it was compressed to the next adjacent belt, which, as herein further disclosed, it does without deformation or breakage, it has its opposite faces free, and hence is in a condition in which such self-readjustment may and does occur. In the disclosed mechanism, I preferably provide for a compression of the dough into a sheet against a belt or apron and the transfer of such dough sheet to another belt or apron, so that during the transfer and upon the second belt or apron, the self-readjustment to which I have referred may occur. I also preferably provide a third belt or apron against which the dough sheet is further compressed and also preferably provide a fourth belt or apron, to which the recompressed sheet is transferred, so that during the transfer and after the sheet is received by said fourth belt or apron further readjustment may occur. Obviously this principle may be continued through any desired number of recompressions and readjustments of the material, but in the disclosed embodiment of the invention, I preferably provide for severing the biscuits from the dough sheet after such second recompression.

In the disclosed embodiment of the invention, I have represented five belts or aprons indicated at A, B, C, D and E. The first of these belts indicated at A is a conveyer belt, upon which the dough mass may be and preferably is placed by hand. The second belt or apron, indicated at B is a compressing belt, and it passes about a compressing roller 2, whereby said belt is driven. Above and sufficiently spaced from the belt B is a co-acting, mass-compressing roll 3, which I shall generally refer to as a mass-compressing, traveling surface. The dough mass is compressed by the rolls 2 and 3 against the belt or apron B into a relatively thick sheet, such sheet sticking or adhering to the belt or apron in such manner that readjustment of the constituents of the dough sheet does not occur while the dough sheet is upon said belt or apron B. Operatively in advance of the compressing belt B is a readjustment-permitting belt or apron C, which is herein shown as having its portion toward the receiving end of the machine underlying the delivery portion of the belt B. This arrangement is, however, not essential to the broad purpose of my invention. As the dough sheet passes from the belt or apron B to the belt or apron C, the described self-readjustment thereof commences and continues while the dough sheet is upon said belt or apron C, inasmuch as the lower surface of the dough sheet does not stick or adhere to such belt or apron C in the same sense in which it adhered to the belt or apron B, because of its compression thereagainst by the roll 3. Operatively in ad-

vance of the belt or apron C is the belt or apron D, which is the second compressing surface. Supported within the same is a roll 4, by which the said belt or apron is driven and constituting with said belt or apron a compressing surface. Seated above and sufficiently spaced from the belt or apron D is a co-acting compressing roll 5, which is preferably spaced a less distance from the belt or apron D than the roll 3 is spaced from the belt or apron B, in order further to reduce the thickness of the sheet. While I may sever the sheet or remove the biscuit portions therefrom, while the same is supported upon the belt or apron D, I preferably effect a second readjustment of the constituents of the sheet, and for this purpose provide a belt or apron E operatively in advance of the belt or apron D, and to which the recompressed sheet is transferred without deformation or breakage. Inasmuch as the sheet is compressed by the roll 5 against the belt or apron D, it has a tendency to stick or adhere thereto, and therefore it has not at such time opposite free faces, so that readjustment of the constituents of the sheet cannot occur. During the transfer of the sheet to the belt or apron E and after its reception by the belt or apron E, the second self-readjustment of the constituents of the sheet occurs. Within the scope of my invention, I may provide for one or more further compressions, and one or more further readjustments of the constituents of the sheet, but preferably I employ some suitable biscuit cutting or like device mounted above the belt or apron E, and not herein shown, which severs biscuit portions from the sheet while supported upon the said belt or apron E. Owing to said readjustments, the biscuit elements when severed, maintain their true form, without shrinkage or expansion.

While I may drive the said belts A, B, C, D and E in any suitable manner for effecting the objects of my invention, I preferably drive said belts at successively increasing speeds through separate mechanisms or trains of devices, so that the speed of each belt may be varied through an extended range, and if desired without varying the speed of any other belt. The particular driving means may be widely varied, but I shall set forth in detail the specific driving means in the disclosed embodiment of my invention, and which I have found in practice to produce excellent results.

Power may be taken from any suitable source and thence conveyed to the sprocket chain 6, which passes about and drives a sprocket gear 7 fast upon a shaft 8 suitably mounted in the framing of the machine. Upon the shaft 8 are splined two cones 9, 10, supporting a driving belt 11 also passing about a second pair of cones 12, 13, splined upon a shaft 14 suitably mounted in the

frame. Said cones are provided with hubs or sleeves to which are suitably connected levers 15, 16, pivoted at 17, 18, upon suitable studs on a girder or other transverse member 19. Each of said levers 15, 16 at one end is provided with a nut 20, mounted respectively upon the right and left hand threads 21, 22 of a suitable screw shaft 23, which may be turned in any suitable manner, as by hand wheel 24, so as to move the members of said pair of cones toward and from each other, and thus to vary the speed of the shaft 14. Upon the shaft 14 is a pinion 23 (see Fig. 6) and meshing therewith is a gear 24 upon a suitably supported shaft 25. Upon said shaft is a pinion 26 meshing with a large gear 27 upon the shaft 28 of the compressing roll 4, and by which the latter is driven at a suitable speed so as properly to 20 drive the belt D. Co-acting with the belt D, if desired, I provide a belt tightener 29 and the said belt at its delivery end passes about a roll or other suitable support 30. Preferably I provide a plate or support 31 directly under the upper run of the belt D, so as to coöperate with the roll 4 for effecting the recompression of the sheet. In the manner described, or in any other suitable manner, the said belt or apron D is driven 30 at a speed which may be varied through an extended range of movement, but which in any event preferably is greater than that of the belt or apron C.

Upon the shaft 8 is a sprocket pinion 32 receiving a sprocket chain 33 passing about a suitable sprocket gear 34 upon a suitably supported shaft 35. Upon the shaft 35 are cones 36, 37 similar to the cones 9, 10 and receiving a belt 38 passing also about similar 40 cones 39, 40, whereby the shaft 41 upon which said cones 39 and 40 are mounted may be driven at a variable speed. Such variation in speed is effected through levers 42, 43 and screw shaft 44 having hand wheel 45 and which need not be more fully described.

Mounted upon the shaft 41 is a sprocket pinion 46 receiving a sprocket chain 47 passing about a sprocket gear 48 upon a shaft 49 suitably supported in the framing of the 50 machine. Adjacent to the shaft 49 is a shaft 50 (shown most clearly in Fig. 7) and upon said shaft are suitably splined cones 51, 52, 53, 54, about which passes a belt 55 and with which coöperate levers 56, 57 adjusted in a manner similar to that already described, by the oppositely screw-threaded shaft 58 having a hand wheel 59. In the manner described, or in any other suitable manner, the shaft 50 is driven at a variable 60 speed.

Upon one end of the shaft 50 is a pinion 60 meshing with a gear 61 upon a shaft 62 suitably mounted in the framing and having thereon a pinion 63 meshing with a gear 64 upon the shaft 65 having fast thereon a

roll 66 about which passes the belt or apron C, whereby said belt or apron is driven at a variable speed, and preferably as described at a speed intermediate that of the belts B and D. Said belt or apron C is suitably supported by rolls or guides 67, 68, 69, and belt tightener 70 and preferably is provided with a flat support 71. Coöperating with the belt or apron C is a suitable spring pressed roll 72 by which the belt or apron C is held in driving engagement with the roll 66.

Upon the shaft 41 is a pinion 73 meshing with a gear 74 upon a shaft 75 having thereon a pinion 76 meshing with and driving a 80 large gear 77 fast upon the shaft 78 of the compressing roll 2, whereby the apron B is driven at a variable speed and preferably at a speed between those of the aprons A and C. The belt or apron B is suitably supported by a roll 79 and a roll or support 80, the latter being mounted in bearing blocks 81 mounted in suitable guides 82 for adjustment by suitable set screws 83. Preferably and as described, the discharge end 90 of the apron B overlaps the receiving end of the belt or apron C, so that the dough sheet is discharged with a slight downward movement from the belt or apron B to the belt or apron C. This permits the commencement 95 of the readjustment of the constituents of the dough sheet as heretofore set forth. Also fast upon the shaft 75 is a sprocket pinion 84 receiving a sprocket chain 85 also passing about a sprocket pinion 86 upon a 100 shaft 87. Adjacent to the shaft 87 is a shaft 88 and upon said shafts are suitably splined cones 89, 90, 91 and 92, similar to those already described and receiving a belt 93. With said cones coöperate levers 94, 95 and 105 an oppositely screw-threaded shaft 96 having a hand wheel 97, whereby the speed of rotation of the shaft 88 may be varied.

Fast upon the shaft 88 is a sprocket pinion 98 about which and a similar pinion 99 110 upon a shaft 100 passes a sprocket chain 101. Upon said shaft 100 is a pinion 102 meshing with a gear 103 upon the shaft 104 of a roll 105, by which the belt A is driven at a variable speed. I preferably provide 115 a spring pressed roll 106 to hold the belt A in driving contact with the roll 104. I also preferably provide a roll or support 107 for said apron and a belt tightener 108. I preferably also provide a flat support 109 120 beneath the upper run of the belt A.

The belt or apron E may be driven in any suitable manner, and if desired from the sprocket chain 6. Preferably, however, the said belt or apron is driven from a shaft 110 125 receiving power from some outside source, not herein indicated. Upon the shaft 110 are mounted cones similar to those already described, but not herein shown. About said cones passes a belt 111 also passing 130

about cones 112, 113 upon a shaft 114. By means of suitable levers 116, 116, shown broken away in Fig. 6, the said shaft 114 is driven at a variable speed in a manner similar to that already described. Upon the shaft 114 is a pinion 117 meshing with a gear 118 upon a shaft 119 and having thereon a pinion 120, itself meshing with a pinion 121 upon a shaft 122 of the roll 123 about which passes the belt or apron E and whereby the latter is driven at a variable speed, but preferably at a speed in excess of that of the belt or apron D. The said belt or apron E is preferably of much greater length than any of the aprons A, B, C and D, but is shown as broken away in Fig. 3. The said belt or apron is supported by the roll or guide 124, and with it co-operates a belt tightener 125 and a spring pressed roll 126, by which the said belt or apron is held in driving engagement with the roll 123. Beneath the upper run of the belt or apron E, I preferably provide a flat support 127. Co-operating with the belt or apron E is a suitable biscuit cutting device by which the biscuit elements are severed from the sheet, the remaining portions of the sheet being separated from the biscuit elements in any suitable manner in the onward travel of the parts.

The compressing rolls 3 and 5 are mounted in suitable blocks 128, 129 respectively, which are mounted for sliding adjustment in guides 130, 131 supported upon the framing of the mechanism. In order to adjust said blocks, I preferably provide threaded shafts 132, 133, one of which, namely, shaft 133, is represented upon an enlarged scale in Fig. 8. Upon the upper ends of said shafts are worm wheels 134, 135 with which co-operate worms 136, 137 upon shafts 138, 139 having thereon hand wheels 140, 141. In this manner the distance apart of the compressing rolls 2 and 3 and the compressing rolls 4 and 5 may be accurately varied.

Preferably I provide some suitable means whereby to indicate for record the distance apart of the rolls of said pairs of rolls. For this purpose, I have most clearly represented in Fig. 8, a scale 142 upon a suitable frame 143 with which co-operate a pointer 144 pivoted at 145 upon said frame and connected to a threaded member 146 connected at 147 to the proper block 128 or 129. I preferably provide means for varying the length of the screw thread member 146, here shown as a turn buckle 148. In this manner, the arm 144 is moved over the scale 142 in accordance with the adjusting movement of the block 128 or 129. Preferably each of the compressing rolls 2 and 4 is provided with a flange 149, 150, which define the lateral edges of the dough sheet.

With certain doughs, it is desirable to pass aprons about the upper compressing

rolls 3 and 5, and for this purpose I have, in Figs. 1, 2 and 3, represented standard 151, 152 respectively having arms 153, 154, 155, 156, whereon are mounted guides 157, 158, 159, 160 about which belts (not shown) 70 may be passed. The guides 158, 160 may be adjusted by screws 161, 162, so as suitably to tension such belts.

The roll 3 constitutes a mass-compressing, traveling surface, and between it and the 75 belt or apron B, the dough is compressed into continuous sheet form. The succeeding belt C is a non-compressing, readjustment-effecting belt or apron onto which the continuous dough sheet is directly delivered by 80 the belt B, and on each succeeding belt C the constituents of the said dough sheet are permitted freely to readjust themselves without compression. The continuous readjusted sheet is directly delivered by the belt or 85 apron C onto the belt or apron D and a bonding, traveling surface, herein represented by the compressing roll C, co-acts with the belt or apron D, to compress said self-adjusted dough sheet thereon. 90

It will be observed that the belts B and C extend past the rolls 3 and 5 respectively toward the delivery end of the mechanism, and so as to support the dough sheet without breakage or deformation past the compressing rolls 2, 3 and 4, 5 respectively. 95

Having thus described one specific embodiment of my invention, I desire it to be understood that although specific terms are employed they are used in a generic and descriptive sense and not for purposes of limitation, the scope of the invention being set forth in the following claims:

1. Continuous dough sheeting and feeding mechanism comprising in combination a 105 mass-compressing traveling surface, a co-acting traveling belt opposed thereto and between which and said mass compressing surface the dough is compressed into continuous sheet form, a succeeding belt onto which said continuous dough sheet is directly delivered by said co-acting belt and on which succeeding belt the constituents of said continuous dough sheet are permitted freely to readjust themselves, another belt onto which the continuous, readjusted sheet is directly delivered by said second belt, and a bonding traveling surface co-acting with said third belt to compress said self-readjusted dough sheet 110 thereon.

2. Continuous dough sheeting and feeding mechanism comprising in combination a mass-compressing traveling surface, a co-acting traveling belt opposed thereto and 125 between which and said mass-compressing surface and dough is compressed into continuous sheet form, a succeeding belt onto which said continuous dough sheet is directly delivered by said co-acting belt and 130

on which succeeding belt the constituents of said continuous dough sheet are permitted freely to readjust themselves, another belt onto which the continuous, re-adjusted sheet is directly delivered by said second belt, a bonding traveling surface co-acting with said third belt to compress said self-readjusted dough sheet thereon, and a fourth belt onto which the continuous sheet 10 is directly delivered by said third belt and whereon said continuous sheet is again permitted to readjust itself.

3. Continuous dough sheeting and feeding mechanism comprising in combination, a mass-compressing, traveling roll, a co-acting, traveling belt opposed thereto and between which and said mass-compressing roll the dough is compressed into sheet form, a succeeding belt onto which said continuous 20 dough sheet is directly delivered by said co-acting belt and on which succeeding belt the constituents of said continuous dough sheet are permitted freely to readjust themselves, another belt onto which the continuous, readjusted sheet is directly delivered by said second belt, and a traveling, bonding, roll co-acting with said belt to compress said self-readjusted dough sheet.

4. Continuous dough sheeting and feeding mechanism comprising in combination, a mass-compressing, traveling roll, a co-acting, traveling belt opposed thereto and between which and said mass-compressing roll the dough is compressed into sheet form, a succeeding belt onto which said continuous dough sheet is directly delivered by said co-acting belt and on which succeeding belt the constituents of said continuous dough sheet are permitted freely to readjust themselves, another belt onto which the continuous, readjusted sheet is directly delivered by said second belt, a traveling, bonding roll co-acting with said belt to compress said self-adjusting dough sheet, 40 and a fourth belt onto which the continuous sheet is directly delivered by said third belt and whereon said continuous sheet is again permitted to readjust itself.

5. Continuous dough sheeting and feeding mechanism comprising in combination, a mass-compressing, traveling surface, a co-acting, traveling belt opposed thereto, and between which and said mass-compressing surface the dough is compressed into sheet 50 form, a compression roll supported within said belt and by which the same is driven, a succeeding belt onto which said continuous dough sheet is directly delivered by said co-acting belt and on which succeeding belt the constituents of said continuous dough sheet are permitted freely to readjust themselves, another belt onto which the continuous, re-adjusted sheet is directly delivered by said second belt, a compression roll supported 60 within said belt and by which the same is driven, a bonding traveling roll co-acting with said third belt to compress said self-readjusted dough sheet.

driven, and a bonding, traveling surface co-acting with said third belt to compress said self-readjusted dough sheet.

6. Continuous dough sheeting and feeding mechanism comprising in combination, a mass-compressing, traveling roll, a co-acting, traveling belt opposed thereto, and between which and said mass-compressing roll the dough is compressed into sheet form, a compression roll supported within said belt 70 and by which the same is driven, a succeeding belt onto which said continuous dough sheet is directly delivered by said co-acting belt and on which succeeding belt the constituents of said continuous dough sheet 75 are permitted freely to readjust themselves, another belt onto which the continuous, re-adjusted sheet is directly delivered by said second belt, a compression roll supported within said belt and by which the same is driven, and a bonding, traveling roll co-acting with said third belt to compress said self-readjusted dough sheet.

7. Continuous dough sheeting and feeding mechanism comprising in combination, a mass-compressing, traveling roll, a co-acting, traveling belt opposed thereto and between which and said mass-compressing roll the dough is compressed into sheet form, a compression roll supported within 80 said belt and by which the same is driven, a succeeding belt onto which said continuous dough sheet is directly delivered by said co-acting belt and on which succeeding belt the constituents of said continuous 85 dough sheet are permitted freely to readjust themselves, a roll within said succeeding belt and by which the same is driven, another belt onto which the continuous, readjusted sheet is directly delivered by said second belt, a compression roll supported within 90 said belt and by which the same is driven, and a bonding, traveling roll co-acting with said third belt to compress and self-readjusted dough sheet.

8. Continuous dough sheeting and feeding mechanism, comprising in combination, a mass-compressing, traveling roll, a co-acting, traveling belt opposed thereto and between which and said mass-compressing roll 100 the dough is compressed into sheet form, a compression roll supported within said belt and by which the same is driven, a succeeding belt onto which said continuous dough sheet is directly delivered by said co-acting 105 belt and on which succeeding belt the constituents of said continuous dough sheet are permitted freely to readjust themselves, a roll within said succeeding belt and by which the same is driven, another belt onto which the continuous, readjusted sheet is directly 110 delivered by said second belt, a compression roll supported within said belt and by which the same is driven, and a bonding, traveling roll co-acting with said third belt to compress and self-readjusted dough sheet.

6
said self-readjusted dough sheet, a fourth belt onto which the continuous sheet is directly delivered by said third belt and whereon said continuous sheet is again permitted to readjust itself, and a roll supported within said fourth belt and by which the same is driven.

9. Continuous dough sheeting and feeding mechanism comprising in combination, 10 a mass-compressing, traveling surface, a co-acting, traveling belt opposed thereto, and between which and said mass-compressing surface the dough is compressed into continuous sheet form, a succeeding belt traveling 15 in the same forward direction as said first belt and onto which said continuous dough sheet is directly delivered by said co-acting belt and on which succeeding belt the constituents of said continuous dough sheet 20 are permitted freely to readjust themselves, another belt traveling in the same forward direction as said first and second belts and onto which the continuous, readjusted sheet is directly delivered by said second belt, and a bonding, traveling surface co-acting 25 with said third belt to compress said self-readjusted dough sheet.

10. Continuous dough sheeting and feeding mechanism comprising in combination, 30 a mass-compressing, traveling surface, a co-acting, traveling belt opposed thereto, and between which and said mass-compressing surface the dough is compressed into continuous sheet form, a succeeding belt traveling 35 in the same forward direction as said first belt and onto which said continuous dough sheet is directly delivered by said co-acting belt and on which succeeding belt the constituents of said continuous dough sheet 40 are permitted freely to readjust themselves, another belt traveling in the same forward direction as said first and second belts and onto which the continuous, readjusted sheet is directly delivered by said second belt, a bonding, traveling surface co-acting 45 with said third belt to compress said self-readjusted dough sheet, and a fourth belt also traveling in the same forward direction as said preceding belts and onto 50 which the continuous sheet is directly delivered by said third belt and whereon said continuous sheet is again permitted to readjust itself.

11. Continuous dough sheeting and feeding mechanism comprising in combination, 55 a mass-compressing, traveling surface, a co-acting, traveling belt opposed thereto and between which and said mass compressing surface the dough is compressed into continuous sheet form, a succeeding belt onto which said continuous dough sheet is directly delivered by said co-acting belt and on which succeeding belt the constituents of said continuous dough sheet are permitted freely to readjust themselves, another belt

onto which the continuous, readjusted sheet is directly delivered by said second belt, a bonding, traveling surface coacting with said third belt to compress said self-readjusted dough sheet thereon, and means to 70 drive said belts at successively higher speeds.

12. Continuous dough sheeting and feeding mechanism comprising in combination a mass-compressing, traveling surface, a co-acting, traveling belt opposed thereto and between which and said mass-compressing surface the dough is compressed into continuous sheet form, a succeeding belt onto which said continuous dough sheet is 75 directly delivered by said co-acting belt and on which succeeding belt the constituents of said continuous dough sheet are permitted freely to readjust themselves, another belt onto which the continuous, readjusted sheet 80 is directly delivered by said second belt, a bonding, traveling surface co-acting with said third belt to compress said self-readjusted dough sheet thereon, a fourth belt onto which the continuous sheet is directly delivered by said third belt and whereon said continuous sheet is again permitted to readjust itself, and means to drive said belts at 85 successively higher speeds.

13. Continuous dough sheeting and feeding mechanism comprising in combination, 90 a mass-compressing, traveling surface, a co-acting, traveling belt opposed thereto and between which and said mass-compressing surface the dough is compressed into continuous sheet form, a succeeding belt onto which said continuous dough sheet is directly delivered by said co-acting belt and on which succeeding belt the constituents of said continuous dough sheet are permitted freely to 95 readjust themselves, another belt onto which the continuous, readjusted sheet is directly delivered by said second belt, a bonding, traveling surface co-acting with said third belt to compress said self-readjusted dough 100 sheet thereon, means to drive said belts at successively higher speeds, and means to vary the speed at which each of said belts is driven.

14. Continuous dough sheeting and feeding mechanism comprising in combination, 115 a mass-compressing, traveling surface, a co-acting traveling belt opposed thereto and between which and said mass-compressing surface the dough is compressed into sheet 120 form, a succeeding belt onto which said continuous dough sheet is directly delivered by said co-acting belt and on which succeeding belt the constituents of said continuous dough sheet are permitted freely to readjust themselves, said co-acting, traveling belt having its delivery end overlapping but close to said succeeding belt and positioned to permit a slight, free, downward movement of the dough sheet without breakage 125 130

or deformation, another belt onto which the continuous, readjusted sheet is directly delivered by said second belt, and a bonding, traveling surface co-acting with said third belt to compress said self-readjusted dough sheet.

15. Continuous dough sheeting and feeding mechanism comprising in combination, a mass-compressing, traveling surface, a co-acting, traveling belt opposed thereto and between which and said mass-compressing surface the dough is compressed into continuous sheet form, a traveling, dough mass-receiving belt positioned to present the 10 dough mass to said bonding, traveling surface and co-acting traveling belt, a succeeding belt onto which said continuous dough

sheet is directly delivered by said co-acting belt and on which succeeding belt the constituents of said continuous dough sheet are 20 permitted freely to readjust themselves, another belt onto which the continuous, readjusted sheet is directly delivered by said second belt, and a bonding, traveling surface coacting with said third belt to compress 25 said self-readjusted dough sheet thereon.

In testimony whereof, I have signed my name to this specification, in the presence of two subscribing witnesses.

KENNETH D. LOOSE.
